CLAIM

The ornamental design for a dispenser for cans or bottles, as shown and described.

DESCRIPTION

FIG. 1 is a perspective view of a dispenser for cans or bottles showing my new design;

FIG. 2 is a front elevational view thereof;

FIG. 3 is a right side elevational view, the left side being a mirror image thereto;

FIG. 4 is a rear elevational view thereof;

FIG. 5 is a top plan view thereof; and,

FIG. 6 is a bottom plan view thereof.
